UNITED STATES PATENT OFFICE

FIELD WHITE, OF DETROIT, MICHIGAN, ASSIGNOR OF ONE-HALF TO BYRON F. EVERITT,
OF DETROIT, MICHIGAN.

OBSERVATION-SHUTTER.

1,203,291.

Specification of Letters Patent. Patented Oct. 31, 1916.

Application filed July 7, 1915 Serial No. 38,623.

To all whom it may concern:

Be it known that I, FIELD WHITE, a citizen of the United States of America, residing at Detroit, in the county of Wayne and State of Michigan, have invented certain new and useful Improvements in Observation-Shutters, of which the following is a specification, reference being had therein to the accompanying drawings.

10 This invention relates to an observation shutter for shielding an observer or operator using a view opening through armor, as in an armored car, an armored vessel, fortifications or other like place, or operating field ordnance or fire arms in the open.

15 The object of the invention is to shield such observer while at the same time giving a substantially unobstructed view through the opening or to protect one otherwise in the open, the device otherwise so arranged as to turn an ordinary light projectile from a rifle or the like and to deflect flying fragments from shrapnel, shells and other bursting projectiles.

20 25 The invention consists in the matters hereinafter set forth, and more particularly pointed out in the appended claims.

In the drawings, Figure 1 is a view in elevation, partially broken away and partially diagrammatic, of an armored motor car equipped with observation shutters that embody the invention; Fig. 2 is an enlarged view in detail of an opening protected by such a shield; Fig. 3 is a view in rear elevation showing a slight modification of the shield and its mounting, and Fig. 4 is a view in vertical section showing one method of operating the shield when it is mounted so as to be shiftable, as indicated in Fig. 3.

30 35 40 Referring to the drawing a circular disk 1 of suitable projectile turning armor plate, is provided with radial slots 2 and is mounted behind an opening as indicated at Fig. 2 in such a way as to be readily rotated at comparatively high speed.

45 As shown in Figs. 3 and 4 one convenient way of mounting the same is by securing it on a spindle 4 that is journaled in a rock arm 5. A bracket 6 affords support for the inner end of the rock arm, which swings on a suitable stud 7. Apertured ears 8 may be brought into alignment with bracket lugs 9 whereby a pin 10 may be thrust therethrough and hold the bracket in either po-

sition desired. A pulley 11, gear wheel or the like on the spindle 4 may be connected with any suitable source of power as by a belt 12 (see Fig. 1) or there may be an electric motor directly connected to the shaft 4, or any other suitable means may be used to impart the necessary motion.

In mounting such a shield or shutter in an armored motor car, the power plant of the car may be used to drive the shutter. By mounting the same on a tilttable bracket or other like means, the shutter may be moved away from in front of the view opening at the will of the operator. When the car is in action, the rapidly moving shutter either in front of the driver or those who are working the guns in the car, gives full protection to the latter, while the slots are passing rapidly enough in front of the eyes of the operator to afford practically unobstructed view. Thus danger from projectiles is minimized and the operator is in comparative safety against small arm fire and shrapnel.

45 It is apparent that such a shutter may be mounted at an advantageous point to protect one sighting a field piece in the open, or may be used to shield one firing a rifle or other small piece, without regard to other armor or like shelter.

Obviously, changes in the details of construction may be made without departing from the spirit of my invention and I do not care to limit myself to any particular form or arrangement of parts.

What I claim is:—

1. The combination with armor having an observation opening, of a circular observation shutter of armor material with radial slots therethrough rotatably mounted in register with the opening and means for rapidly rotating the shutter.

2. The combination with armor having an observation opening, of an observation shutter, formed of a circular plate of armor material with slots therethrough, means rotatably mounting the shutter in register with the openings, and means for rapidly rotating the shutter.

3. The combination with an armored motor car, of armor thereon having observation openings, rotatable observation shutter disks for the openings of armor material with narrow slots therethrough, and means to rotate the shutter disks at high speed,

the slots being disposed to turn the shot and to permit clear vision when the disks are rotating.

4. A projectile turning observation shutter having narrow observation openings therethrough and means for rapidly rotating the shutter.

5. The combination with armor having an observation opening, of a projectile turning shutter plate, means for rotatably mounting the plate, and means for rapidly rotating the plate, the plate being provided with a plurality of narrow observation openings with the greatest direction of length trans-
15 verse to the direction of rotation.

6. An observation shutter consisting of a plate of armor material with radial narrow

slots therethrough, means rotatably mounting the shutter, and means for turning the shutter rapidly.

7. An observation shutter consisting of a rotatable armored plate with narrow slots therethrough and means for rapidly rotating the plate, the slots being so disposed in relation to the axis of motion of the plate 25 as to prevent passage of shot and permit practically unobstructed vision therethrough when the plate rotates at high speed.

In testimony whereof I affix my signature in presence of two witnesses.

FIELD WHITE.
